UNITED STATES PATENT OFFICE.

GEORGE A. BURNHAM, OF SAUGUS, MASSACHUSETTS, ASSIGNOR, BY MESNE ASSIGNMENTS, TO CONDUIT ELECTRICAL MANUFACTURING CORPORATION, OF BOSTON, MASSACHUSETTS, A CORPORATION OF MASSACHUSETTS.

ELECTRICALLY-OPERATED ELECTRIC SWITCH.

Application filed September 9, 1921. Serial No. 499,406.

To all whom it may concern:

Be it known that I, GEORGE A. BURNHAM, a citizen of the United States, residing at Saugus, in the county of Essex and State 5 of Massachusetts, have invented an Improvement in Electrically-Operated Electric Switches, of which the following is a specification.

This invention relates to oil immersed 10 electric switches particularly adapted to be automatically controlled, as automatically opened and automatically closed.

In automatic sub-station work, the oil switches are opened and closed automatically 15 through a relay system and without operation or supervision by an attendant.

The ability of an oil immersed switch to interrupt its circuit under load depends upon the maintenance of an effective head of 20 oil in the switch above the switch members at the point at which the circuit interrupting arc is drawn. When an oil immersed switch is interrupted under a severe load, oil may be expelled from the oil receptacle 25 of the switch and the oil level within the switch consequently may be reduced. When the switch opens under severe load conditions, or opens repeatedly under less severe load conditions, such an amount of oil may 30 be thrown from the switch as to expose the switch members and if the switch is again opened, the next circuit interrupting arc may occur in air, or in the gaseous contents of the interior of the switch; or at least the 35 oil level within the switch may become so reduced that the arc may burst through the oil and into the gas-expansion space above the oil in the switch. Under such conditions of affairs, serious explosions and fires 40 may occur. Inasmuch as there is no attendant near the switch, the reduced and dangerous oil level within the switch can not be known and guarded against.

An object of this invention is to provide 45 an oil immersed electric switch with means governed by the oil level within the switch to make known the oil level.

A further object of the invention is to provide an oil immersed electric switch with 50 means governed by the oil level therein to control and govern the operation of the switch and, specifically, to govern the control circuit for the switch and to render inoperative said circuit to operate the switch

when the oil in the switch is dangerously 55 low.

In carrying out these objects of the invention, I provide a float within the oil receptacle, or otherwise disposed, to be moved in response to changes in the level of oil 60 in the receptacle. Said float is arranged to govern the movable member of an auxiliary switch which is adapted to be associated with the control circuit of the oil immersed switch. Said oil-level governed auxiliary 65 switch is so arranged that it will not govern the controlling circuit when the oil level in the switch is sufficiently high but, when the oil level within the switch descends to a predetermined low point, the auxiliary switch 70 will operate to govern the control circuit and prevent the operation of the switch or, at least, the opening of the switch, until the oil level is again restored in the switch.

A further object of this invention is to 75 provide an oil-level governed auxiliary switch as an attachment to existing oil switches.

A further object is to generally improve the construction, operation and control of 80 an oil immersed electric switch.

Fig. 1 is an elevation of a three-pole electrically-controlled oil-immersed electric switch embodying the invention.

Fig. 2 is a sectional detail through a 85 switch unit of Fig. 2 and illustrating in particular the oil-level governed auxiliary switch.

Fig. 3 is a sectional detail of the switch of Fig. 2 in a position to control the controlling circuit for the switch.

Fig. 4 is a sectional detail of a modified form of auxiliary switch.

Fig. 5 is a top view, in detail, of the auxiliary switch of Fig. 1.

Fig. 6 is a diagram of the switch and control circuit therefor embodying the invention.

As here shown, a three-pole switch has been selected to illustrate the invention, and the switch comprises the switch frame 10 having three oil receptacles 11 removably depending therefrom. Three sets of stationary switch-members 12 are carried by said frame and are immersed in the oil in said receptacles and three movable switch members 13 are also immersed in the oil in said receptacles and connected with the operat-

ing mechanism 14. Said switch is adapted to be operated by electrically controlled devices wherein 15 is the closing coil and 16 is the trip coil associated with the switch 5 operating mechanism 14. The oil-level governed auxiliary switch comprising a part of this invention is preferably supported 10 removably from the switch frame 10, and preferably a separate auxiliary switch is associated with each oil receptacle. Said auxiliary switch may include the float 17 secured on the end of an arm 18 disposed within the oil receptacle 11. Said arm 18 may be pivotally carried by the bracket 19 15 which is secured dependingly from the switch frame. Said float 17 is adapted to be partially immersed and float in the oil in said receptacle to rise and fall in accordance with variations in the oil level. 20 An insulating block 20 may be secured to the top of the switch frame and may have the two stationary contact members 21 secured thereto. Said contact members are adapted to be included in an electric circuit 25 arranged to govern the controlling circuit for the switch. A bridging member 22 is carried adjustably on the upper end of a rod 23 and said rod is guided for vertical movement in the insulating block 20. Said 30 rod extends below the switch frame and may be provided with a forked end 24 between which the float arm 18 may be disposed. A pin 25 may be extended between the forks of said rod and through a slot 26 in the float arm whereby to connect said rod 23 and arm 18 loosely.

In the normal position of the oil level within the receptacle as shown in Fig. 2, the float is adapted to support the bridging 40 member 22 some distance above the contact members 21 whereby the auxiliary switch will be ineffective in governing the controlling circuit for the oil switch. When, however, the oil level in the switch descends to 45 some low position by reason of expulsion of oil from the switch when the circuit is opened under heavy load, said float 17 will descend with the oil level and eventually move the bridging member 22 into contact with the contact members 21, as indicated in Fig. 3, and close the circuit associated therewith and govern the controlling circuit as will hereinafter be set forth.

The particular form of mechanism connecting the float 17 with the bridging member 22 may be varied to fulfill different requirements.

In Fig. 4 a modified form of mechanism is illustrated, and the bridging member 22 is secured to the upper end of a tubular member 23^a which is slidably received in the insulating block 20. The float 17 is secured to a stem 18^a and said stem is adjustably received within said tubular member 23^a 65 and secured thereto in adjusted position by

means of the set screw 27. With this arrangement the float is connected directly to the bridging member and the distance between the float and bridging member may be varied to provide for differences in positions of normal oil level in different oil receptacles. 70

The switch embodying the invention is usually provided with an auxiliary switch governed by a movement of the main switch. 75 As here shown, said latter auxiliary switch includes the movable switch member 30 which is adapted to bridge the set of contact members 31 when the main switch is closed and to bridge a second set of oppositely disposed contact members 32 when the switch is opened, as is usual practice. The control circuit adapted automatically to control the opening and closing of the switch and be governed by the oil-level governed auxiliary 80 switch is illustrated in Fig. 6.

The control circuit includes the overload relay 35 which is adapted to be energized upon a predetermined overload in the circuit 36 controlled by the oil immersed switch 90 to operate to bridge its contact member 37. The bridging of the contact members 37 serves to energize the trip coil 16 from the auxiliary power circuit 38 through the contact members 31 and bridging members 30 95 of the auxiliary switch of the main switch. When the main switch opens, said bridging member 30 will be moved away from said contact members 31 thereby to open the trip coil circuit, and said bridging member 30 will be moved to bridge the contact member 32 to condition the control circuit for the closing of the switch.

The control circuit is usually provided with means arranged automatically to control the closing of the switch and cause the switch to be closed successively a predetermined number of times separated by predetermined time intervals, and thereafter open the switch and lock it open. The switch closing means includes a definite time limit relay 39 and the notching relay 40. The bridging of the contact members 32 of the auxiliary switch when the main switch moves to open position, operates to close the circuit through the definite time limit relay 39, the notching relay 40, the contact members 41 of the notching relay 40, all in series, to the auxiliary power circuit 38. The definite time limit relay 39 is provided with a suitable retardation device as the dash pot 39^a which serves to retard the action of the movable element of the relay for a predetermined period, whereby to permit the switch to remain open a predetermined period of time as, say thirty seconds, or thereabouts. At the expiration of the predetermined period of time, the bridging member 39^b of said relay will be moved upward to bridge the contacts 39^c and thereby 100 105 110 115 120 125 130

- close the circuit of a hesitating relay 42. Said hesitating relay 42 is of more or less common construction and when energized is arranged to bridge its contacts 43 and there-
 5 by close the circuit of the closing coil 15. Said coil operates to close the switch and, in the movement of the switch mechanism to the closed position, the auxiliary switch member 31 will be moved from bridging po-
 10 sition with the contacts 32 and shifted into contact with the contacts 31, thereby dis-
 abling the closing circuit and permitting the notching relay 40, the definite time limit 39 and the hesitating relay to reset and con-
 15 ditioning the control circuit to govern the opening coil 15 of the switch. The hesitating relay 42 is so arranged that, when ener-
 gized, its circuit-controlling member will be moved immediately to close the circuit
 20 and will be held in circuit-closing position by suitable means, not necessarily shown, to permit the switch-closing mechanism suf-
 ficient time to operate and then will drop back and break the circuit controlled by it.
 25 The notching relay 40 is of more or less common construction and is here diagram-
 matically shown. It may include the move-
 able switch member 40^a which is pivoted on the shaft 40^b and is arranged to be held
 30 either in a position to bridge the contact 41 or in an open position by the spring 40^c. A notching disc 40^d may be pivoted on said shaft 40^b and the notches are arranged to be engaged successively by the latch 40^e
 35 of the actuating coil 40. A dash pot 40^f and its spring 40^g may function to return said notching disc 40^d slowly from a moved position to its initial position.
 When the switch closing circuit including
 40 the time limit relay 39 and the notching relay is energized to close the switch, the latch 40^e will be moved upwardly to rotate the disc by the space of a notch. If the switch is closed, and remains closed, the notched
 45 disc will return gradually to its position. If, however, the switch is tripped open within a few seconds, the latch 40^e will be moved upwardly by the coil 40 to advance the disc a second notch. If the switch is again
 50 tripped open, the disc will again be advanced by the space of another notch and in this last movement may move the pin 40^h adjustably carried in it against said bridging arm 40ⁱ and cause it to separate from the
 55 contacts 41; and the spring 40^c will hold said bridging member away from said contacts and thereby disable the circuit and the switch will consequently remain open until the notching relay is reset by an operative.
 60 The oil-level governed auxiliary switch embodying my invention is included in a cir-
 65 cuit 45 in which is included a relay 46. When the oil level in the switch descends to a dangerously low point, the contact mem-
 bers 21 of said switch are bridged by the bridging member 22 and said relay 46 is energized and operates to move its bridg-
 ing member 47 away from bridging position with the contact members 48 in the auxiliary power circuit 38, which controls the control
 70 circuit. Consequently, the control circuit is disabled and will be inoperative to control the switch until the oil level in the switch is again restored.
 If desired, some form of alarm device, as
 the indicating lamp 49, may be included in
 75 said circuit 45 to direct the attention of an
 attendant to the fact that the oil level in
 the switch is dangerously low and the con-
 trol circuit is out of commission.
 80 The control circuit may include the
 manually operable remote closing switch 50
 and opening switch 51 with the appropriate
 signal devices as the lights 52 and 53 and
 associated with the elements of the auto-
 85 matic controlling circuit in the usual man-
 ner.
 I claim:
 1. An oil immersed electric switch having
 90 associated with it an auxiliary switch ar-
 ranged to be governed by the level of oil
 within said oil immersed switch, and means
 governed by the auxiliary switch to con-
 trol the operation of the oil switch.
 2. An oil immersed electric switch hav-
 95 ing a closing coil, and means governed by
 the level of oil in said switch to control the
 operation of said closing coil.
 3. An oil immersed electric switch hav-
 100 ing a closing coil and an opening coil, and
 means governed by the level of oil in said
 switch to control the operation of said coils
 on said switch.
 4. An oil immersed electric switch hav-
 105 ing operating means therefor and means as-
 sociated with said operating means and gov-
 erned by the level of oil in the switch to
 prevent the operation of the switch when the
 oil level therein is dangerously low.
 5. An oil immersed electric switch hav-
 110 ing electrically-actuated means for operat-
 ing it and means governed by the fluid level
 in said switch to control said operating
 means.
 6. An oil immersed electric switch hav-
 115 ing automatic electrically-actuated operat-
 ing means for it, an auxiliary switch ar-
 ranged to control said operating means, and
 means governed by the oil level in said
 oil immersed switch to govern said auxiliary
 120 switch.
 7. The combination of a receptacle adapt-
 ed to contain a fluid, an electrical appara-
 tus immersed in the fluid, a control system
 for said apparatus, and means governed by
 125 the fluid level in said receptacle to govern
 the operation of said control system.
 8. An electric switch including a switch
 frame, an oil receptacle, switch members im-
 130 mersed in the oil in said receptacle, a float re-

sponsive to variations in level of the oil in said receptacle and an auxiliary switch arranged to be operated by said float and switch-operating means governed by said auxiliary switch.

9. An electric switch including a switch frame, an oil receptacle, switch members immersed in the oil in said receptacle, a float responsive to variations in level of the oil

in said receptacle, and an auxiliary switch arranged to be operated by said float when the oil level reaches a predetermined low position, and switch-operating means governed by said auxiliary switch.

In testimony whereof, I have signed my name to this specification.

GEORGE A. BURNHAM.
